UNITED STATES PATENT OFFICE.

HARLAN M. BRITAN, OF OJUS, FLORIDA.

STOVE.

Application filed January 20, 1925. Serial No. 3,659.

This invention relates to an improvement in oil stoves or the like and has for its object the provision of a stove wherein heat is efficiently generated with economy in the 5 consumption of fuel and safety in the operation of the burner and in which the heat from one burner may be advantageously utilized to simultaneously heat a number of lids and consequently a number of cooking 10 utensils or the like to secure the full heating effect of the burner and to prevent waste of the heated products of combustion.

Another object resides in the provision of a burner having the advantages and capacities enumerated and which is susceptible of convenient and graduated control and also of simple and durable construction, reliable and safe in use and easy and comparatively inexpensive of manufacture.

Other objects and advantages reside in certain novel features of the construction and arrangement of parts which will be hereinafter more fully described and particularly pointed out in the appended claims, 25 reference being had to accompanying drawings forming a part of this specification and in which:

Figure 1 is a perspective view showing one embodiment of the invention;

Figure 2 is a plan view thereof;

Figure 3 is a detail view in elevation of one of the lids, the adjacent portion of the body of the stove being shown in section;

Figure 4 is a view in vertical section on line 4—4 of Figure 2;

Figure 5 is a view in vertical section on line 5—5 of Figure 4;

Figure 6 is a fragmentary view in section on line 6—6 of Figure 2;

Figure 7 is a detail perspective view of the plug of the burner; and

Figure 8 is a view in section on line 8—8 of Figure 2, and

Figure 9 is a detail view of the oil inlet pipe.

Referring to the drawings, the numeral 1 designates generally an oil stove which has a lower shelf 2 supported on legs 3, sides 4, a top 5 and a back 6. Of course the structure 50 of the stove thus far described may be varied. A plurality of lids designated at 7, 8, 9 and 10 are supported on the top of the stove, the lids being fitted in openings pro-

vided for the same in the top and having ribs 11 which engage the top around the 55 openings to support the lids in position. The lids are of substantially annular form and each has an inwardly inclined or bevelled top wall 12 adapted to support cooking utensils of various sizes in such manner that 60 the base of the cooking utensil closes the opening defined by the annular lid in the top of the same.

Means is provided for supplying heat to the lid 10 and this means includes a burner 65 having a cup member 13 supported at the upper end of an oil inlet pipe 14. The upper end of the oil inlet pipe 14 is threadedly connected with the base of the cup member 13 at its center and projects above the bottom of the base so that dirt and sediment will be deposited on the bottom of the base and will not fall back into the oil inlet pipe. The pipe 14 is filled up with wires so as to restrict the quantity of oil to the amount 75 necessary to supply the requirements of the burner. In lieu of the wires a rod which is smaller than the bore of the pipe may be fitted in the pipe. The interstices between the wires or the interstice between the rod 80 and the pipe provide the passageway for the oil. This feature is one of safety and prevents conflagration or explosion. A plug 15 is set in the cup member 13 and has an opening 16 centrally of its base to receive the 85 upper end of the oil inlet pipe 14. Slots 17 are also provided in the base of the plug and extend from the opening 16 to the periphery of the plug. The plug 15 is somewhat smaller than the cup member 13 to 90 provide a wick receiving space 18 in which a wick 19 is fitted. The upper end of the plug 15 is reduced to provide a shoulder 19' on which a combined wick holder and chimney support 20 rests. The combined wick 95 holder and chimney support 20 comprises an inner perforated sleeve 21 and an outer perforated sleeve 22 between which the wick 19 is fitted. The sleeve 22 carries spider arm 23, the outer ends of which are connected to 100 the lower section 24 of the chimney designated generally at 25 and made up of the section 24 and a section 26 connected with the lid 10. Between the sections 24 and 26 a sleeve 27 of asbestos is provided. As shown 105 in Figure 5 the lower end of the section 24

is spaced from the cup member 13 to provide the air inlet around the burner and upper end of the chimney extends through the open bottom of the lid 10.

5 A casing designated generally at 30 encloses the burner and chimney and may consist of sheet metal sections 31 and 32 between which a layer 33 of asbestos is disposed. The asbestos is extended over the 10 upper edges of the sections 31 and 32 and engages the under side of the top 5 of the stove. The section 31 is adjustably supported as at 34 on the shelf 2 of the stove and the section 32 is carried on the section 15 31. A hinged door 35 is incorporated in the section 31. By adjusting the section 31 the top of the casing may be pressed firmly against the underside of the top 5 and prevent the escape of the warm air or gases. 20 thereby enhancing the efficiency of the stove to a very material extent.

The oil is supplied through the inlet pipe 14 through a supply line 40 from a tank 41 in which a safety oil feed connection 42 25 forming the subject matter of my co-pending application Serial Number 202,937 is embodied. In this supply line 40 a control valve 43 is also embodied and has an angular finger 44 fixed to the axis of the hand wheel 45 by which the valve is adjusted. This finger 44 coacts with a bracket 46 having a curved portion 47 bearing numbers 48 so that the adjustments of the valve may be made with precision. A stop lug 49 is 30 integrally formed with the bracket 46 and limits the turning movement of the valve to such position as to supply the minimum amount of oil necessary to keep the burner lighted. A shut off valve 50 is also incorporated in the supply line.

45 Means is provided for affording communication between the lids 7, 8, 9, and 10 so that the heat from the one burner serves to heat all the lids. For this purpose the adjacent or confronting portions of adjacent lids are cut away or formed with openings 55 and connections 56 are provided to form closed conduits between the openings 55. Except for the openings 55 the periphery of the lids may be solid. These connections 56 may be advantageously constituted of sheet metal plates 57 extending between adjacent lids and fitted in notches formed in the lids. The plates 57 are 50 held in position by U-shaped cross plates 58, the plates 58 being more properly of inverted U-shaped form and having attaching lugs 59 fastened to the stove top. A bottom plate 60 having an asbestos facing 61 is provided on the bottom of each connection 55. The lids 7, 8, and 9 have integrally formed therewith bottom plates 62 so that all of the lids have closed bottoms 60 except the one lid to which heat is supplied directly from the burner. The under side 65

of the top of the stove and the bottom plate 62 of the lids may be covered by sheet metal having an asbestos facing.

The lid 7 is formed with an outlet 65 for the gases.

70 The plug 15 is provided with an apertured lug 15^a to facilitate handling.

With this arrangement a single burner may be used to effectively heat a plurality of lids so that a number of cooking utensils 75 may be simultaneously heated from a single burner. In this way the heated gases which are ordinarily wasted are utilized to the fullest extent so that a high economy in the use of fuel is effected and efficient heating 80 action is had. The invention has a further advantage in that the cost of providing an individual burner for each lid is avoided.

The burner structure provided insures the 85 efficient generation of a high degree of heat and due to the fact that the gases are confined when all of the lids are used until they have passed out through the outlet 65 odors and fumes are eliminated since complete combustion is had. Of course it is to be 90 understood that when the lids are used cooking utensils rest on the beveled top walls thereof and close the open tops of the lids to prevent escape of the gases.

95 As shown in Fig. 9 the burner pipe 14 has a filler rod 14^a provided therein to define a restricted passage 14^b for the fuel. In lieu of the fuel rod 14^a the pipe 14 may be filled with wires and the interstices to the 100 wires provide the restricted passage for the fuel. By restricting and retarding the flow of the fuel through the burner pipe to the amount necessary to proper combustion safety in operation is assured.

105 I claim:

1. In a stove, a plurality of lids, each lid having an opening in its top and having a wide smooth and inwardly bevelled surface on its top designed to receive and snugly fit the lower portions of cooking utensils of various sizes to provide for the closure of the open top of each lid by the cooking vessel supported thereon, means for supplying heat to one of said lids, connections extending between the sides of the lids for affording communication between the lids whereby the heat is distributed throughout the lids when the same are closed by cooking vessels, all of said lids except the one to which heat is supplied having closed bottoms.

110 2. In a stove, a plurality of lids, each lid having an opening in its top and having a top surface designed to receive cooking utensils, the lids being of substantially annular form, means for supplying heat to one of said lids, and connections extending between the sides of the lids for affording communication between the lids whereby the heat is distributed throughout the lids, the confronting portion of the lids having open- 115 120 125 130

ngs receiving the connections, the connections consisting of plates extending between the lids and cross plates securing said first mentioned plates in position, all of said lids except the one to which heat is supplied having closed bottoms.

3. In a stove having a shelf and a top, a

lid of annular form, a burner, a chimney between the burner and the lid and a vertically movable casing for the burner and the chimney adjustably supported on the shelf and engageable with the top.

HARLAN M. BRITAN.
